LOBSTER MUZZLE

Ernest Ward Ashton, Ottawa, Ontario, Canada,
assignor to Ketchum Manufacturing Company,
Limited, Westboro, Ontario, Canada, a
corporation of Ontario, Canada

Application March 2, 1936, Serial No. 66,772

3 Claims. (Cl. 17—1)

This invention relates to lobster muzzles.

It is of importance in the lobster industry to prevent captured live lobsters from losing their claws and to this end it is important to hold the movable jaw of each claw from movement. Ordinarily, when a number of lobsters are confined together they tend to fight and it is well known that when a claw is injured the lobster may readily discard it which results in a loss of a valuable portion of the meat. In the past it has been usual to prevent the movable jaw of a lobster's claw from moving by inserting between the movable jaw and the claw, at the point where the former is hinged to the latter, a wooden plug which has been driven into the claw, thus holding the movable jaw in fixed position. However, the use of plugs of this character causes the lobster to lose vitality and will generally injure the lobster so that on the one hand the recovered meat is not of as good a quality and on the other hand, injury of this character may cause the lobster to discard his claws, resulting in the loss of the delicate meat of the claws. It has also been proposed to use rubber bands to encircle the jaws of each claw thereby to hold the movable jaw stationary. However, rubber bands, it is apparent, will deteriorate very quickly and apart from this they are rather difficult to put on.

It is therefore an object of the present invention to avoid the disadvantages of present practice and to provide a simple type of muzzle which can be readily applied to lobster claws and which will hold the movable jaw stationary without injuring the claw.

A further object of the invention is to provide a practical article of this character which can be manufactured readily and marketed economically.

With these and other objects in view the invention consists essentially in a muzzle formed from a single piece of metal of greater length than width to provide a band adapted to encircle a lobster's claw, the band having at least one portion cut out along its length to form at least one slot, preferably to receive a projection of the claw, the cut out portion being integrally connected with the band and having one end free to form an integral tie member, the latter being bent over the band and projecting beyond the end thereof. Preferably the band is provided with two cut out portions forming a pair of ties projecting beyond the ends of the band, one of the slots formed by the cut out portions providing means for receiving a projection on the

claws of the lobster and the division between said slots abuts the projection on the lobster's claw, facilitating the application of the muzzle to the claw. In addition each tie member is preferably given a channel-like form to facilitate locking, as fully described in the following specification and illustrated in the accompanying drawing.

In the drawing:

Figure 1 is a front elevation of the preferred form of muzzle.

Figure 2 is a fragmentary rear elevation of the muzzle shown in Figure 1.

Figure 3 is a section taken on the line 3—3 of Figure 1.

Figure 4 is a rear elevation of a band formed with flat tying members.

Figure 5 is a pictorial illustration of a lobster's claw showing the muzzle applied thereto.

Figure 6 is an enlarged fragmentary elevation of an alternative form of construction.

Figure 7 is a rear elevation of a further alternative form of construction employing only one tie, and

Figure 8 is a transverse section taken through a lobster's claw, showing the type of muzzle illustrated in Figure 7 applied to the claw.

Referring to the drawing, and particularly to Figures 1-3, A indicates the muzzle as a whole which consists of a single piece of metal forming a band 10 of greater length than width, which is adapted to encircle the claw of a lobster. The band is cut out along its length to form separated slots 11 and 12, the division between the slots being provided by an integral strip of metal 13 extending transversely of the band. The portions 14 cut out to form the slots 11 and 12 are bent away from the band, one end integrally connecting with the band, the opposite free end and the major part of said portion extending over and beyond the ends of the band to provide tie members of appropriate length. One of the slots 11 and 12 is designed to receive a projecting member 15 which is located on an outer edge of the movable jaw 16 of a lobster's claw B the projection being common in all lobsters and occurring on the movable jaw at a point directly adjacent to the hinge 17 (see Figure 5).

In mounting the muzzle upon the claw, the projection 15 is permitted to protrude through one of the slots 11 or 12 and the strip 13 is brought to abut the projection 15 whereby the band is folded around the claw and, with the strip 13 abutting the projection 15, the free ends of the band are positively positioned adjacent to the

opposite edge of the claw so that the ties 14, which then lie adjacent to each other projecting beyond said opposite edge of the claw, may be grasped and twisted to lock the muzzle on the 5 claw.

It will be apparent, having regard to the fact that the gradually curved surface of the claw is elongated in character, that the band cannot slip off the claw once locked and the projection 15 10 further serves to prevent the muzzle from moving to any decided degree upon the claw.

The tie members 14 are, according to the preferred form of construction, bent to channel shape as indicated at 18, see particularly Figure 15 3, thus to provide tie members of semi-rigid character whereby they will readily twist one upon the other in a very simple operation and provide a relatively strong structure of tie. Tie members, of course, may be left in their natural 20 state as struck from the band, namely flat as shown in Figure 5, but when using this type of tie member the twisting operation is a little more difficult and the ties are not as substantial.

In Figure 6 I have shown a structure wherein 25 an additional slot 19 is formed substantially midway between the ends of the band 10 to receive the projection 15 on the lobster claw, the additional slot being separated from the slots 12 and 11 by integral transverse strips 20 and 21, 30 either of which may be engaged with the projection 15. In addition, I have also shown a projecting offset apron 22 which may engage the surface of the movable jaw of the claw, the apron 22 abutting that part of the claw in which the 35 movable jaw is hinged and extending over a portion of the hinge.

In Figure 7 I have shown a slightly modified form of band which is very similar to the forms described with the exception that only one tie 40 member 14 is provided, the cut-out portion from the slot 12 having been completely severed. The slot 12 therefore acts as part of the securing means co-operating with the tie 14 and the integral strip 13 is so positioned that when the 45 projection 15 on the claw protrudes through the slot 11 the end of slot 12 is positioned adjacent to or projecting over the opposite edge of the claw whereby the single tie member 14 may be projected through the slot 12 and bent over to 50 one side of the claw, as shown in Figure 8, so that the muzzle is then locked on the claw. The

tie member 14 in this form of construction may be and preferably is of channel form.

In the foregoing it will be realized that I have provided a lobster muzzle which may be easily applied to and locked upon the lobster claw so that it cannot be displaced and which will not injure the claw. It will be apparent also that the construction is relatively durable and can be readily manufactured in quantity and marketed at an economical figure. 5 10

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims. 15 10

I claim:

1. A lobster muzzle comprising a single piece 20 of metal of greater length than width forming a band adapted to encircle a lobster claw, said band having a portion cut out along its length to form at least one slot for receiving a projection on the claw, said portion cut out from said band having one end free and its opposite end connected integrally with the band to form an integral tie member, the latter being bent over the band and a major portion projecting beyond one end thereof, said tie member being bendable 25 to secure the band around a claw. 30

2. The device as claimed in claim 1 in which the integral tie member is of channeled cross section.

3. A lobster muzzle comprising a single piece 25 of metal of greater length than width forming a band adapted to encircle a lobster claw, said band having portions cut out along its length to form at least one slot for receiving a projection on the claw, said portions cut out from said 40 band having one end free and their opposite ends connecting integrally with the band to form integral tie members, the latter being bent in opposite directions over the band and projecting beyond the opposite ends thereof, said tie members 45 lying adjacent to one another when said muzzle is folded around a lobster claw whereby they may be twisted together to lock the muzzle on the claw. 50

ERNEST WARD ASHTON.
